GENERATOR REGULATOR

Henri S. de Malaussene, Santa Monica, Calif., assignor to Adolph L. Bernheimer, Santa Monica, Calif.

Application April 6, 1932, Serial No. 603,612

2 Claims. (Cl. 290—7)

The present invention relates to a regulator and more specifically to a regulator which is adapted to regulate the output or charging current of a motor vehicle generator.

5 When the engine of the motor vehicle is idling at a speed below ten miles per hour, which occurs when driving through traffic, or due to stop and go signals, the output of the generator which is driven by the motor of the motor vehicle is below 10 the normal charging rate of the battery and as a result the battery does not receive its normal charge and the life thereof is shortened.

This is especially true now that the majority 15 of motor vehicles are equipped with free wheeling and it is one of the objects of the present invention to provide a regulating device which is actuated by the foot throttle control to bring the generator output up to a maximum normal charging rate while running at slow speeds.

20 Another important object of the invention is to provide a regulating device which may be readily installed in any make or type of motor vehicle.

The invention contemplates the provision of a variable resistance in series with the shunt field 25 of the generator and the field regulating brush and an electrical contact connected in shunt with the variable resistance and actuated by the foot throttle control of the motor vehicle for automatically closing the electrical contact when the 30 motor vehicle is running at a slow speed and upon pressing the foot throttle control to open the contacts to permit the field current to pass through the resistance and thereby maintain the output charging current of the generator 35 substantially constant.

In the accompanying drawing, forming a part of this application and in which like numerals are employed to designate like parts throughout the same,

40 Figure 1 is an electrical diagram of connections illustrating the manner in which the variable resistance is connected in the shunt field and in which the electrical contact is connected to the foot throttle of a motor vehicle,

45 Figure 2 is a curve in which the ampere output is plotted against the miles per hour of the ordinary generator now in use,

50 Figure 3 is a curve in which the ampere output is plotted against the miles per hour of the present invention,

In the drawing, wherein for the purpose of illustration is shown a preferred embodiment of the invention, the numeral 2 represents diagrammatically, the armature of a usual battery charging generator which is driven by the engine of

the motor vehicle. The output brushes 4 and 6 are connected by conductors 8 and 10 to the usual battery 12 of the motor vehicle.

The field 14 has one terminal connected to the brush 4 through the conductor 8 and the other terminal is connected through conductor 36, to a variable resistance 16 which is connected through conductor 18 to the field regulating brush 20. Connected in shunt with the variable resistance 16 is a make and break switch, which consists of an L-shaped switch 22 mounted on a support 24 and provided at one end thereof with a contact 26 which is normally associated with a stationary contact 28 mounted on a support 30. The contact arm 22 is connected by means of conductors 32 to one terminal of the variable resistance 16 and the stationary contact 28 is connected through the support 30 and the conductor 34 to the movable arm 36 of the resistance 16, thereby connecting the contact arm 22 and its associated stationary contact 28 in shunt with the variable resistance 16.

The contact arm 22 is provided with an aperture through which there is arranged a rod 36 which is securely held in position therein by means of a screw threaded nut 38. The rod 36 passes through an L-shaped guide member 40 and interposed between the stop member 42 on the rod 36 and the L-shaped guide member 40 is a spring 44 which urges the contact arm 22 out of its normally electrically closed position.

The outer end of the rod 36 is provided with a ring which engages a ring on a rod 46 which is connected to the foot throttle 48 of the motor vehicle. As is clearly indicated, the foot throttle is normally maintained in the idling position by means of the spring 50 secured to the lower portion thereof through the aperture 52. The foot throttle is pivotally mounted on a supporting rod 54 and in the normal idling position of the throttle the contact 26 of the contact arm 22 engages its associated contact 28 thereby shunting out the variable resistance 16.

In installing the device it is only necessary to set the field regulating brush 20 to the full output of the generator which is about 20 amperes on all standard cars, then adjust the resistance 16 until the ammeter on the dash reads about 15 amperes which is a safe charging rate when the switch is open and the engine of the motor vehicle is running at high speed. When the engine of the motor vehicle is idling or running at slow speed, too slow to supply the battery with its normal charging current, the spring 50 urges the foot throttle 48 to its outer position, which

is indicated in dotted lines, and thereby moves the electrical contact arm 22 until its contact 26 engages the stationary contact 28, shorting out the resistance 16 and thus permitting more current to flow through the field 14, which will, in turn, bring the generator's output up to a maximum output or charging rate, although running at slow speeds.

Figure 2 is a curve illustrating the output charging current of the ordinary generator which is not equipped with the present regulating means. As is clearly illustrated in this curve, when the motor vehicle is running at slow speeds and consequently driving the generator at a slow speed, say for example, 10 miles per hour, there is not output current and the generator does not provide a sufficient output charging current to the battery until the motor vehicle has reached a speed of substantially 25 to 30 miles per hour.

In Figure 3 there is shown a curve in which the ampere output current is plotted against the miles per hour of the vehicle which drives the generator. It will be seen from this curve that the normal output charging current of 15 amperes is reached at the usual idling speed of 10 miles per hour and from a speed of 10 to 35 miles per hour, the output of 15 amperes is substantially constant.

The variable resistance 16 enables the output of the generator to be set substantially at any output value. If so desired, the control mechanism controlling the actuation of the electrical switch for shorting out the variable resistance may be included within the generator, the same being built as a single unit.

It will be readily appreciated that the device may be installed on any standard make of car employing the three brush generator and that it will not only supply the battery with a constant charging current, but will also prevent the generator from burning out.

While there is shown only one embodiment of the invention in the accompanying drawing, it is capable of various changes and modifications

without departing from the spirit thereof and it is intended therefore that only such limitations shall be imposed thereon as are indicated in the prior art or in the appended claims.

Having thus described the invention, what is claimed is:—

1. In combination with a third brush motor vehicle generator having a third brush adjustment, adapted to charge the battery of the motor vehicle, a variable resistance in the field circuit of said generator whereby the third brush may be positioned at the maximum output position and the field current adjusted by varying the variable resistance to select a constant output current, a make-and-break switch connected in shunt with said resistance, a throttle mechanism for controlling the speed of the engine of the motor vehicle, and means connecting the throttle mechanism of the motor vehicle and the make-and-break switch for opening said switch upon the actuation of said throttle mechanism, whereby said constant output current is maintained over a broad range of speeds of the motor vehicle.

2. In combination with a third brush motor vehicle generator having a predetermined third brush adjustment adapted to charge the battery of a motor vehicle, a resistance in the field circuit of said generator, the third brush being positioned at its maximum output position, a make-and-break switch connected in shunt with said resistance, a throttle mechanism for controlling the speed of the engine of the motor vehicle, and means connecting the throttle mechanism of the motor vehicle and the make-and-break switch for opening said switch upon the actuation of said throttle mechanism, said resistance being of a value to give the desired third brush regulation when the resistance is effective and to provide for a constant output current whereby said constant output current is maintained over a broad range of speeds of the motor vehicle.
